(57) **CLAIM**

The ornamental design for a shark life vest, as shown and described.

DESCRIPTION

FIG. 1 is a right side view of the shark life vest of the present invention, the left side view being a mirror image thereof;

FIG. 2 is a front view thereof;

FIG. 3 is a back view thereof;

FIG. 4 is a top view thereof; and,

FIG. 5 is a bottom view thereof.

The drawing is lined for color.

The dash markings shown in the drawings represent a pattern simulating two tones of the same color.
